Fig. 1 is a plan view of a fabric, showing my new design, and

Fig. 2 is a sectional view of the puffed textile fabric of Fig. 1 along the line 2—2.

The design is embodied in a puffed textile fabric having a surface of raised puffs arranged as shown in Fig. 1. Interlaced threads, such as represented by the bottom horizontal line in Fig. 2, hold the puffs raised.

I claim:

The ornamental design for a puffed textile fabric, as shown and described.
